FASTENER-SETTING MACHINE

Philip B. Jensen, Naugatuck, Conn., assignor to Scovill Manufacturing Company, Waterbury, Conn., a corporation of Connecticut

Filed Nov. 17, 1961, Ser. No. 153,015

6 Claims. (Cl. 1—104)

This invention relates to an apparatus for setting complementary snap fastener elements upon a cardboard blank.

The principal object of this invention is to automatically feed cardboard blanks one at a time by means of a conveyor mechanism to a pair of fastener-setting units where each blank is stopped and complementary fastener elements are simultaneously attached in a predetermined position. After attachment of the fastener elements, the blank is fed to a discharge unit while the next succeeding blank is automatically fed to the attaching units.

Another object is to provide sensing and safety controls that will stop the conveyor feed mechanism and fastener-setting units should any malfunction occur. This could be in the form of a failure to feed a blank to the fastener units, feeding more than one blank at a time, or failure of one or both fastener units to attach a fastener.

A further object is to provide a means for adjusting the fastener-setting units relative to a common support so that the spacing of the fastener elements on the blank may be varied.

Other objects and advantages to be attained will be apparent as the description proceeds and the novel features of the invention will be particularly set forth in the appended claims.

In the drawings:

FIG. 1 is a perspective view of the conveyor mechanism and the fastener-setting units embodying my invention;

FIG. 2 is a plan view of the same;

FIG. 3 is a side view of one of the sensing switches;

FIG. 4 is an end view of the same;

FIG. 5 is a detailed view of a portion of the blank-feeding mechanism;

FIG. 6 is an end view of the ratchet control for the blank stop fingers;

FIG. 7 is a schematic view of the electrical circuit and units used in conjunction with my invention;

FIG. 8 is a lay-out view of one type of blank to which fastener elements may be attached by my apparatus;

FIG. 9 is a perspective view of a blank as it appears when folded up and held in closed position by the fasteners;

FIG. 10 is a perspective view of a type of stud element that may be set by my apparatus; and,

FIG. 11 is a similar view of a type of socket element.

The function of the hereinafter-described machine is to simultaneously attach complementary fastener elements in a predetermined position on a cardboard box blank. FIG. 8 shows a blank 10 of generally square shape in which are formed fold lines that define a rectangular box body 11, arranged diagonally to the generally square outline of the blank, and a series of closure flaps and tongues. When folded up with tongues tucked in and flaps overlapped, the blank 10 will form a generally rectangularly shaped box as shown in FIG. 9, that is adapted to contain a measured amount of material, such as bacon.

The overlying closure flap 12 located along one of the longitudinal sides of the box body 11, is provided with a

2

transparent window 12a thereby providing a suitable opening through which the contents of the box may be viewed. A snap fastener element 13 is attached adjacent the tip of the overlying flap 12 and a complementary fastener member 15 is attached to the opposite underlying flap 14 which is preferably deeply notched as at 16 to afford a clearance for the transparent window 12a. When folded, the blank 10 is adapted to be retained in closed box-like form by the engagement of the attached fastener elements 13 and 15 which, for purpose of illustration, are shown as being a socket and a stud, respectively.

The fastener elements 13 and 15 are of the type wherein the attaching means for the elements are integral therewith and specifically, as shown, are provided with bendable attaching prongs projecting out of the flange on said elements on the same side as the engaging parts.

The principal units of the apparatus consist of a blank holding and feeding unit 17, a belt conveyor mechanism 18, a blank discharge unit 19, a stud fastener attaching unit 20 and a socket fastener attaching unit 21. The feeding unit 17, the conveyor mechanism 18 and the discharge unit 19 are of the general type of mechanism used in an addressograph machine except modified to interfit with the fastener-setting units 20 and 21 and to accommodate the blank 10.

The blanks 10 are adapted to be stacked upon the feeding unit 17 from which they are fed one at a time to the conveyor unit 18 by a pusher block 22 resting on the stack of blanks 10. The block 22 is actuated to slip the top-most blank from the stack by link 23 and lever 24 fixed to an oscillating shaft 25 (see FIG. 5). The individual blanks 10 will be fed in between a series of pinch rolls 27 and continuously travelling belts 26 where each blank will be caught and transported lengthwise of the conveyor mechanism 18 until stopped by a pair of stop fingers 28 supported on a common shaft 29 that is arranged transversely of said conveyor mechanism.

Fastener-Setting Units

40 The fastener-setting unit 20 consists of a stud-setting machine 20a and a motor 31 mounted upon an adjustable plate 30, the motor 31 operating the machine 20a through a belt drive 32. The machine 20a has a setting station X positioned inwardly of the right side of the conveyor mechanism 18.

Likewise, the fastener-setting unit 21 consists of a socket-setting machine 21a and a motor 39 mounted upon an adjustable plate 38, the motor operating said machine through a belt drive 40. The machine 21a has a setting station Y positioned inwardly of the left side of the conveyor mechanism 18.

The stud and socket fastener-setting machines 20a and 21a are of the general type shown in the Carpinella Patent 2,735,567.

One of the desirable features of my invention is to mount the fastener-setting units 20 and 21 in such a manner that one of the units can be adjusted perpendicularly to the longitudinal axis of the conveyor mechanism while the other unit is mounted to be adjusted parallel to the longitudinal axis of said conveyor mechanism. This provides a means for adjusting the spacing of the fastener elements to accommodate different sizes of blanks or whatever articles may be fed to the machine to have fasteners applied thereto. For this reason, each fastener-setting machine with its motor is mounted on a common

adjustable plate so that movement of the plate will cause each machine and its motor to be moved as a unit.

Specifically, the stud fastener-setting unit 20 is designed to be adjusted perpendicular to the conveyor axis. For this purpose, the plate 30 has on its underside a longitudinal groove 33 interfitted with a guide rail 34 that is attached to the top of a common support table 35. The adjustment of the plate 30 is accomplished by a jack screw 36 operated by a handle 36a. After an adjustment is made to plate 30, the latter may be secured to the table 35 by tightening clamps 37 bolted to said table.

The socket fastener-setting unit 21 is designed to be adjusted parallel to the conveyor axis. For this purpose, the underside of the plate 38 is formed with a pair of transverse grooves 41 interfitted with a pair of spaced guide rails 42 that are secured to the top of support table 35. The plate 38 may be adjusted by a jack screw 43 operated by handle 44 and held in adjusted position by clamps 38a bolted to the table 35.

Mechanical Controls

The means for feeding the blanks 10 one at a time from the feed unit 17 has been previously described in part as consisting of the pusher block 22, linkage 23 and 24 and oscillating shaft 25.

In order to impart oscillatory motion to shaft 25, the outer end of said shaft has a crank lever 45 attached thereto which in turn is operated by a long reciprocating rod 46 having an angled end 46a suitably connected to said crank lever 45. The rod 46 may be slidably supported in bearing blocks (not shown) fixed on the frame of the conveyor 18. The opposite end of the rod 46 is connected to the outer end of lever 47 which is pivoted in bearing block 48 mounted on plate 38. The inner end of lever 47 is operated by a barrel cam 49 that is keyed to the drive shaft 50 of the attaching machine 21a so that as the drive shaft 50 revolves, reciprocating motion will be imparted to rod 46 and oscillating motion to shaft 25.

The mechanism for stopping and releasing the blank 10 (shown in phantom outline FIG. 2) in the conveyor 18 has been partially described previously as stop fingers 28 and the common oscillating shaft 29. It is to be noted that the shaft 29 is arranged above and transversely of the conveyor 18 and pivots in bearings 51 and 52 mounted on the framework of the conveyor. The means for oscillating the shaft 29 is best shown in FIG. 6 and consists of a ratchet dog 53 mounted on the outer end of said shaft adjacent the bearing 51. When fingers 28 are in blankstopping position, the ratchet dog 53 will be engaged in a notch 54a of a cam ratchet wheel 54 which is rotatably mounted in bearing 51. Counterclockwise motion is imparted to the ratchet wheel 54 by a spring-tensioned pawl 55 carried by a block 56 adjustably mounted on a longitudinal bar 57 that is slidably mounted on the conveyor frame 18 parallel to the rod 46. The opposite end of the bar 57 is connected to the angled end 46a of the rod 46 from which the bar 57 obviously receives a reciprocatory motion. Each time the bar 57 is reciprocated, the pawl 55 will index the ratchet wheel 54 one tooth thereby causing the dog 53 to ride up over the outer surface of a tooth and into the next notch thus raising and lowering the stop fingers 28. It is to be noted that the outer surface of each tooth of the ratchet wheel 54 has a rather broad expanse over which the nose of the ratchet dog 53 is adapted to ride. This assures that the stop fingers 28 will be held in elevated position for a sufficient time period to permit the blank 10, after the setting operation, to be propelled well on its way by the conveyor 18 before the dog 53 drops into the next succeeding notch of said ratchet wheel and permits said stop fingers to drop into the path of the next conveyed blank.

When blanks of a different size are to be fed to the attaching units, it may become necessary to change the

position of the stop fingers 28. This can be done by changing the position of the rod 29 which can be adjusted longitudinally of the framework of the conveyor 18 by loosening the set screws on bearings 51 and 52 and sliding the bearings along the frame of the conveyor. For a finer adjustment to predetermine a more exact positioning of the blank 10 in relation to the setting stations of the units 20 and 21, the stop fingers 28 are also adjustably mounted on the shaft 29 by cleats 58 and set screws 59 (see FIG. 1).

When rod 29 is moved for adjustment purposes, the block 56 will have to be moved a corresponding distance. This is done by loosening the set screws 56a and sliding the block 56 along the bar 57 until the pawl 55 properly engages the ratchet wheel 54; after which, the set screws 56a may be tightened.

Electrical Controls

Various electrical devices are provided to control the operation of the fastener-setting units 20 and 21 through solenoid-operated clutches. These devices will prevent said units from operating until a blank is properly positioned in line with the setting stations, and will also stop said units if any malfunction occurs, such as feeding more than one blank at a time or failure of one or both fastener units to attach a fastener. The electrical devices and circuits which include an electronic interval timer, are diagrammatically shown in FIG. 7 in which the main power lines are indicated by L₁ and L₂.

The fastener-attaching machines 20a and 21a are driven by constantly running motors 31 and 39 through solenoid-operated one-revolution clutches 70 and 71. The clutch-controlling solenoids 72 and 73, connected directly to line L₂, are operated by a normally open self-energizing contact relay CR through the normally open limit switch LS₁ and contact CR₂ of said relay that is connected to line L₁. The interposed limit switch LS₁ will be closed when contacted by the leading edge of a box blank 10 just prior to the positioning of the blank by stop fingers 28. When relay CR is energized and LS₁ is closed, the circuit to the clutch solenoids 72 and 73 will be completed, the clutches engaged and the attaching machines 20a and 21a started. If a blank is not in proper fastener-attaching position, switch LS₁ will remain open thereby breaking the circuit to the clutch solenoids 72 and 73, thus preventing operation of the attaching machines.

The contact relay CR connected directly to line L₂ is controlled by an electronic interval timer T through the normally closed stop switch S which is connected to line L₁, normally open timer switch TS, normally closed limit switch LS₂ and contact CR₁ of relay CR which makes said relay self-energizing. A normally open two-stage start switch will initially energize relay CR through switch S₁, after which it will be controlled by the timer T.

The timer switch TS will be closed and will remain closed for a preset interval when the timer receives an electrical impulse upon completion of an internal circuit across the terminals 81. The preset timed interval is slightly longer than the speed at which the blanks 10 are fed to the attaching units so that under normal operating condition, an impulse will be received by the timer before the timed interval is completed thereby initiating a new timed interval which will keep the switch TS closed, relay CR energized and the attaching units operating. If due to a malfunction, no impulse is received and the timed interval is completed, the switch TS will open causing the contact relay CR to de-energize thereby stopping the attaching machines 20a and 21a. The normally closed limit switch LS₂ will open only if two or more blanks are fed through the conveyor unit 18, and the stop switch provides a means to manually stop the attaching machines 20a and 21a. Operation of either of the latter switches will, of course, de-energize relay CR.

The internal impulse circuit of the timer consists of

the normally open impulse switches IS_1 and IS_2 that are located adjacent to and directly in line with the setting stations of the attaching units 20 and 21 parallel to the line of travel of the blank. As the blank 10 with fasteners attached is fed from the attaching station to the discharge unit, the impulse switches will be closed simultaneously by the combined thickness of the blank 10 and the attached fastener members (as described below) thereby sending an impulse to the timer. Should one or both of the attaching units 20 and 21 fail to attach a fastener, one or both impulse switches will fail to close, thereby allowing the timed interval of the timer to complete which will cause switch TS to open and de-energize relay CR thus stopping the attaching machines 20a and 21a. When the attaching machines are first started, the initial impulse to the timer will be provided by the second stage S_2 of the start switch.

As the supports for the impulse switches IS_1 and IS_2 are substantially the same except for left and right hand mountings, it is considered sufficient to describe only the left hand switch IS_1 as viewed in FIG. 2.

As shown in FIGS. 3 and 4, impulse switch IS_1 is supported by a bracket 74 that is connected to the base of the attaching machine 21a through an angle piece 75. A hinging plate 76 is pivotally connected to the bracket 74 as at 77, and carries on its outer end a movable guide shoe 78 that is provided with a downwardly flared leading end 78a. The outer end of the hinging plate 76 is in direct contact with the plunger of the impulse switch IS_1 so that any downward movement of said plate will cause switch IS_1 to close. A stationary shoe 79 with an upwardly flared leading end 79a is supported directly above the movable shoe 78 by means of spaced angle braces 80 that are bolted to bracket 74. The shoes 78 and 79 are directly in line with the setting station of attaching unit 20 so that the blank 10 and the attached fastener elements are guided between the shoes by the flared ends 78a and 79a when fed from the attaching station to the discharge unit.

The space between the shoes 78 and 79 is great enough to permit passage of the blank 10 with no movement to the lower hinged shoe 78 but small enough so that the combined thickness of the blank 10 with an attached fastener member will cause the lower shoe to be deflected downwardly thereby closing the impulse switch IS_1 . It will thus be seen that while the blank with attached fastener will close the impulse switches, the blank alone will fail to actuate said switches, thereby stopping the attaching machines.

Operation

To operate the machine after the motors for the fastener-attaching units 20 and 21 and the conveyor 18 are started, it will first be necessary to manually feed one of the blanks 10 from the stock of blanks in unit 17 to the conveyor 18 where it will be caught between the pinch rolls 27 and the belts 26 and fed along the conveyor until the leading edge of said blank contacts fingers 28 as a stop. Just prior to the time the blank 10 contacts the stop fingers 28, it will also contact and close switch LS_1 . Pushing the start button S_1 will close relay CR which in turn will energize solenoids 72 and 73 thereby engaging the clutches 70 and 71. The start button will also initiate a timed interval in the timer T so that operation of the machine will now be fully automatic.

Operation of the clutches 70 and 71 will cause the units 20 and 21 to run through a single cycle of operation to set the socket and stud elements 13 and 15 at their respective positions on blank 10 as shown in FIG. 8. Upon the single revolution of the main shaft 50 of unit 21, the cam 49 will rotate and through lever 47, rod 46, crank 45 and shaft 25 operate the pusher block 22 to feed another blank to the conveyor 18. Simultaneously the bar 57 will be moved to operate the ratchet wheel 54 and dog 53 to elevate the stop fingers 28 and release the

previous blank and allow it to be carried by conveyor 18 to the discharge unit 19 where the blanks 10 with elements properly attached may be packed for shipping. When the first blank leaves the fastener-attaching station, the blank 10 with fasteners attached will close the impulse switches IS_1 and IS_2 thereby initiating a new timed interval so that the contact relay CR will remain energized. With no blanks in the fastener-attaching station, the switch LS_1 will return to its normally open position until contacted by the next succeeding blank which will close LS_1 causing another pair of fasteners to be attached.

From the above-described mechanisms, it will be obvious that after the first blank is fed by hand, the operation of feeding blanks and setting fastener elements 13 and 15 thereupon, will be continuous unless there is a malfunction of one or more units whereupon all operations will be stopped by the electrical controls described in connection with FIG. 7.

What I claim is:

1. In an apparatus for applying a pair of complementary snap fastener elements to a blank which when folded upon itself is held in closed position by said elements, said apparatus comprising a holding and feeding unit for a stack of said blanks, a blank-conveying mechanism continuously operating in one direction, a pair of fastener-setting units, one located on each side of said conveying mechanism, means for feeding a single blank from said holding and feeding unit to said conveying mechanism, means for advancing said blank along said conveying mechanism, means to stop said blank in line with said setting units, means contacted by said advancing blank for actuating said setting units through a single cycle of operation for attaching said fastener elements, and means operated from one of said setting units for releasing said stop means after the fastener-setting operation.

2. In an apparatus as defined in claim 1 wherein said holding and feeding unit is operated directly from one of said fastener-setting units.

3. In an apparatus of the class described comprising a fastener-setting unit and a continuously operating conveyor for feeding blanks to said unit, said unit comprising a main drive shaft, a clutch drive for said shaft, a solenoid control for said clutch drive, stop means operated from said drive shaft to arrest the movement of said blanks in said conveyor in line with the setting station of said unit, a contact relay, and a contact switch interposed between a normally closed switch of said contact relay and said solenoid, said contact switch adapted to be engaged by the travelling blank in said conveyor at about the same time it contacts said stop means to energize said solenoid and operate said unit through a single cycle of a fastener-setting operation.

4. In an apparatus of the class described comprising a fastener-setting unit having a setting station and a continuously operating conveyor for feeding blanks to said unit, said unit comprising a main drive shaft, a clutch drive for said shaft, a solenoid control for said clutch drive, stop means operated from said drive shaft for stopping a blank in the conveyor prior to the fastener-setting operation and to release said blank after the setting operation, and interval timer having a set timed cycle as determined by the speed of the blanks being fed through the conveyor, a contact relay controlled by said timer, said relay being energized during said timed cycle, and an impulse switch connected to said timer and arranged to be contacted by an element set on said blank for closing said impulse switch and reactivating said timed cycle.

5. In an apparatus as defined in claim 4 wherein a limit switch is interposed between a switch in said interval timer and said contact relay, said limit switch adapted to be opened upon the feeding of two or more blanks at the same time through said conveyor and serving to de-energize said contact relay.

6. In an apparatus of the class described comprising a pair of fastener-setting units having fastener-setting stations for setting complementary fastener elements on a blank and a continuously operating conveyor for feeding blanks to said units, said units being disposed one on each side of said conveyor, each of said units comprising a main drive shaft, a clutch drive for said shaft, a solenoid control for said clutch drive, stop means operated from one of said units for stopping a blank in the conveyor prior to the fastener-setting operation and to release said blank after the setting operation, an interval timer having a set timed cycle slightly greater than the speed of the blanks being fed through the conveyor and fastener-setting units, a contact relay controlled by said timer, said relay being energized during said timed cycle, and a pair of

10

15

normally open impulse switches connected to said timer, one located beyond the fastener-setting station of each unit in a line parallel to the conveyor axis and adapted to be closed by the fastener elements set upon said blank for reactivating said timed cycle.
